WILLIAM O. WORTH, OF CHICAGO, ILLINOIS, ASSIGNOR OF TWO-THIRDS TO
WILLIAM R. DONALDSON, OF LOUISVILLE, KENTUCKY, AND HENRY W.
KELLOGG, OF BATTLE CREEK, MICHIGAN.

FRictional Driving-Wheel.

SPECIFICATION forming part of Letters Patent No. 659,427, dated October 9, 1900.

Application filed November 6, 1899. Serial No. 785,954. (No model.)

To all whom it may concern:

Be it known that I, WILLIAM O. WORTH, a citizen of the United States, residing in Chicago, county of Cook, and State of Illinois, have invented certain new and useful Improvements in Friction Driving-Wheels; and I do hereby declare the following to be a full, clear, and exact description of the invention, such as will enable persons skilled in the art to which it appertains to make and use the same.

My invention relates to improvements in friction driving-wheels.

The object of my invention is to provide a friction-wheel for the transmission of power the surface of which shall be made of such a material so applied to the body of the wheel as to possess a very high coefficient when in frictional contact with a driven wheel which it is designed to rotate.

My wheel is especially designed for motors used on motor-vehicles, and it is especially applicable to the transmission of power when fixed to the main shaft of a gas-engine and associated with a wheel upon a shaft placed at right angles to the main shaft, the speed of the driven wheel being determined with relation to the driving-wheel upon the location of the former along the face of the latter.

In the drawings, Figure 1 is a sectional view of my driving-disk, of cast-iron or similar material, before the frictional material has been applied, showing the rim a^2 in section. Fig. 2 is a section through line 2 2 of Fig. 1 with the friction material applied.

A disk a , having a hub a' , is fixed to shaft b . A rim a^2 extends around the disk a and overlaps friction-surface c , and grooves a^3 are cut into the surface of the wheel, as shown. Radial grooves a^4 are also cut into the face in a similar manner and of equal depth. These grooves may be made wider at the bottom, if desirable, for the purpose of retaining the material that is to be forced therein more securely.

The material which I propose to use for friction-surface c is a product of rubber or a material having similar characteristics. I press the material into the grooves while it is

in a plastic state and then vulcanize it while it is in place. Pressure may be applied to the face of the friction-surface during the time that the vulcanizing process is going on. The degree to which this process of vulcanizing is continued will be determined by experience. I have found that when the material is approximately semivulcanized it will then possess the desired quality. The circumferential grooves are cut into the face of the disk a to prevent the material c from spreading radially, and those which are cut into the face in radial lines prevent it from creeping around the wheel when pressure is applied to the face of the disk by the contact with the driven wheel. The rim a^2 holds it in place. Ordinary rubbergum when applied to a wheel and treated in the manner described possesses features that are very desirable for the purpose set forth. The coefficient of friction between the driving and driven wheel is very high. The yielding surface of the driving-wheel, as a result of its yielding elastic nature, affects a greater surface contact between the surface of driving and driven wheel than is possible when two unyielding surfaces are used for the purpose.

Another highly-valuable quality possessed by my invention is the fact that when the driven wheel, mounted upon a shaft practically parallel with the face of the driver, said wheel having a travel thereon within the limits of the said face, is driven thereby the speed may be changed by increasing or decreasing the revolutions of the driven wheel in very small increments or decrements as the driven wheel may be positioned at a longer or shorter radius of the driver. This characteristic is not new in my invention; but heretofore this ideal method of changing the power and speed of the driven wheel could not be utilized when inflexible or unyielding surfaces are used on account of its low efficiency and the great noise made by the unyielding surfaces of the driving and driven wheels when in contact.

My device may be operated to a very great advantage on motor-vehicles, as its efficiency is very high and it is almost entirely noise-

less, or on any kind of machinery where it is desirable to secure the advantages described. By using an elastic surface on the face of the driving-wheel and by tapering the face of the driven wheel properly the differential action due to the unequal speed of the driving-wheel where it makes contact at various points on its radius across the face of the driven wheel, which is always present when unyielding surfaces are used, is avoided. The driven wheel should be tapered so that the portion of its face farthest from the center of the driving-wheel is slightly larger in diameter than that portion near the center of the driver, and when contact is made between the driving and the driven wheel the yielding material of the driver will be somewhat more depressed at this point, and by this means the speed relation across the face of the driven wheel will become more uniform than it is possible to obtain with the usual device of this nature. I have found that the material

described and which I use for this purpose remains unaffected by the weather and in every way is adapted to the use set forth. 25

Having described my invention, what I claim as new, and desire to secure by Letters Patent of the United States, is—

A driving-wheel for the transmission of power, comprising a supporting-disk having 30 grooves in the face thereof, a yielding, frictional material secured in the said grooves, the said disk having an overlapping rim extending inwardly from the periphery over the face of the said material, substantially as set forth.

In testimony whereof I have signed this specification, in the presence of two subscribing witnesses, this 1st day of November, 1899.

WILLIAM O. WORTH.
